UNITED STATES PATENT OFFICE

1,920,648

ATHLETIC SUPPORTER

Charles K. Lane, Rockland, Mass.

Application January 26, 1933. Serial No. 653,575

1 Claim. (Cl. 128—160)

This invention relates to protective devices known as athletic supporters and worn chiefly by athletes to protect certain body members.

The invention is an improvement on that disclosed by my Patent No. 1,868,610, dated July 26, 1932.

The supporter shown by said patent includes an elastic waist band, a pouch depending from the front portion of the waist band, elastic buttock straps depending from side portions of the band, and an oblong crotch pad composed of a piece of sheet felt, having a narrow forward end portion attached to the lower end of the pouch, and a wide rear end portion attached to the lower ends of the buttock straps.

The object of the present invention is to provide an improved construction of the crotch pad having the advantages hereinafter set forth.

Of the accompanying drawing forming a part 20 of this specification,—

Figure 1 is a perspective view showing the supporter as it appears when ready to be donned.

Figure 2 is a rear view showing the supporter donned.

Figure 3 is a fragmental view showing a top view of a portion of the pouch, portions of the buttock straps and a crotch pad including a rear end member formed by end portions of the buttock straps, and a forward end member attached to said rear end member and the pouch.

Figure 4 is a view showing the parts shown by Figure 2 separated from each other.

Figure 5 is a section on line 5—5 of Figure 3.

Figure 6 is a section on line 6—6 of Figure 3.

Figure 7 is a section on line 7—7 of Figure 3.

Figure 8 is a view similar to Figure 7 showing the flexed condition of the crotch pad when the supporter is donned, as shown by Figure 2.

Figure 9 is a side view of the felt blank from 40 which the forward crotch pad member is formed.

The same reference characters indicate the same parts in all of the figures.

In the drawing, 12 designates the waist band, 13 the pouch depending from the front portion of the waist band, and 15—15 the buttock straps depending from the side portions of the waist band, said parts being composed of woven fabric such as elastic webbing.

The construction of the waist band and pouch may be in all respects as disclosed by my former patent above mentioned, the pouch being formed to support a body member, and to be fastened at its lower end to a crotch pad.

The buttock straps 15 differ from those shown 55 by said patent in that their lower ends constitute

a laminated rear crotch pad member integral with the straps.

In carrying out the present invention I construct the crotch pad as next described.

The buttock straps 15 have transverse lower 60 end edges at right angles with their longitudinal edges, said edges defining strap extensions 16—16 so formed that when they are overlapped, or superposed, one on the other, and united by stitches 17, as shown by Figures 3 and 4, they 65 collectively constitute a substantially rectangular laminated rear crotch pad member, composed of two layers, each integral with a strap, said member being adapted to bridge and conform to the lower portion of the wear's rump 70 crease 19, and to conform to the rear portion of the crotch.

The rear member thus formed has an angular corner portion 18 formed to project into the rear portion of the wearer's crotch. Said portion 18, 75 composed wholly of woven fabric, is suitably flexible, so that although it is normally flat as shown by Figure 7, it may be flexed as best shown by Figure 8, and conform yieldingly to the rear portion of the crotch.

The crotch pad includes a narrow compressible forward member formed and arranged to extend through the narrow portion of the crotch from the lower end of the pouch 13 to the corner portion 18 of the rear pad member.

The forward pad member shown separately by Figure 4 is formed from an oblong blank of relatively thick sheet material, preferably felt, shown by Figure 9. Said blank includes a body portion 20 and edge portions 21 which are folded over the body portion and constitute ears 22 secured to the body portion by stitches 23. The ears 22 are provided with obliquely extending end edges 24 exposing seats 25 on the opposite ends of the body portion. The lower end portion of the pouch 13 and the corner portion 18 of the rear pad member are secured to the seats 25 by stitches 26.

It will now be seen that the rear pad member, integral with the elastic buttock straps 15, has a desirable degree of flexibility enabling it to conform yieldingly to the lower portion of the rump crease and the rear portion of the crotch, and is at the same time less expensive and more durable than a rear pad member composed wholly of felt, as heretofore.

The supporter is characterized by the facts that the layers of the rear crotch pad member are integral with the buttock straps, and that the area of the blank from which the forward pad member

100

105

110

is formed is reduced to a minimum. A considerable saving in the cost of the material of the forward member is therefore effected, the saving being particularly noticeable when the material is compressible felt.

I claim:

An athletic supporter including a waist band, a pouch depending from the front portion of the waist band, buttock straps depending from the side portions of the waist band, said waist band, pouch and buttock straps being of woven fabric, the lower ends of said straps being overlapped and stitched together to form a laminated rectangular flexible rear crotch pad member adapted to bridge and conform to the lower portion of the wearer's rump crease, and conform to the

rear portion of the crotch, and a narrow oblong compressible forward crotch pad member composed of a blank of compressible sheet material having a body portion and ears folded over and stitched to the body portion, and provided with obliquely extending end edges exposing seats for the pouch and the rear pad member on the ends of the body portion, the lower end of the pouch and a corner portion of the rear crotch pad member being stitched to said seats, the supporter being characterized by the facts that the layers of the rear crotch pad member are integral with the buttock straps, and the area of the blank from which the forward crotch pad member is formed is reduced to a minimum.

CHARLES K. LANE.
